UNITED STATES PATENT OFFICE

2,396,976

BLAST FURNACE

George A. Whitehurst, Mount Lebanon, Pa., assignor to Carnegie-Illinois Steel Corporation, a corporation of New Jersey

Application January 18, 1944, Serial No. 518,765

7 Claims. (Cl. 266—32)

This invention relates to blast furnaces as used in the steel industry, and particularly to an improved lower inwall for the same and similar shaft-type metallurgical furnaces.

As presently constructed, blast furnaces usually are lined throughout with fire-clay brick. The quality of this brick is adjusted to meet the particular requirements of different zones of the furnace which are divided into four sections or parts; namely, the hearth, bosh, lower inwall and upper inwall. The brick of the hearth is subjected to the action of high temperature and slag without being required to stand any loads or abrasion. On this account, its properties are selected to show a maximum resistance to temperature and chemical action. In the bosh section, the brick is subjected to a very high temperature, attack by the slag, and some abrasive action of coke passing over it, but again it is not required to stand any load. Its characteristics are adjusted for high chemical inertness and temperature stability without any particular attention to the mechanical properties. In the lower inwall, the brick must meet the requirements almost equal to those of the bosh section from slagging and temperature standpoints, and at the same time must support the weight of the entire lining on the inside of the shaft and stand severe abrasion caused by descending charge. Its properties must, therefore, combine good resistance to chemical action and temperature as well as a high mechanical strength and abrasion resistance at the temperatures involved. Properties of brick used for lining the upper inwall are directed principally towards exceptionally high abrasion resistance with but little attention both to the chemical stability and capability of standing high temperatures.

Advances made in the manufacture of refractories permit to a great extent the meeting of the requirements of three of the above mentioned zones; namely, the hearth, bosh and upper inwall section. The fire brick as now produced is capable of withstanding both temperature and the chemical action involved as well as abrasion in the upper inwall. The temperature in the lower part of the inwall of a contemporary blast furnace varies usually between 2450 and 2300° F. and a very pronounced softening of fire-clay brick occurs at around 2200° F. Consequently, it will be seen that in order to support the heavy weight of the superimposed lining, the lower portion of the inwall must be made excessively thick. Only a few years ago

the generally accepted thickness of lining for this portion of the blast furnace averaged closely to 60 inches, and even now it cannot be reduced without endangering the operation to less than 40 inches.

Impossibility of obtaining the desired properties by use of brick itself led blast furnace technicians to provide the additional required characteristics to the vital parts of the furnace by means of artificially cooling the lining. This practice became standard as far as the bosh and hearth section was concerned and spread very widely towards the lower portion of the inwall. In designing a blast furnace, the lining of bosh sections is relieved from any superimposed loads, so that it has to stand only the temperature and chemical action of operating conditions. On this account, weakening inwall lining by placing in it voluminous cooling devices as used in the bosh section cannot be tolerated, though cooling practice used in the construction of the latter adequately meets the requirements. Present design of the lower inwall prevents, however, the application of water cooling or any other type of cooling to the lower portion of the inwall to the extent of assuring the desired effect.

The inwall lining, which begins at the mantle plate, is at all times subjected to compression exerted by many tons of brick superimposed on it. This pressure must be absorbed by the resistance of the brick at this level, greatly softened by temperature. A substantial reduction of temperature within the corresponding areas can be effected by placing in the lining a sufficient number of cooling boxes of the type used in the bosh section, but this practice leads to a pronounced weakening of the lining. Cooling boxes, which are hollow castings with comparatively thin walls, have a far lower compression strength than brick, and even at a comparatively low temperature of their operation are not in a position to support the load normally imposed on brickwork. Limitations placed thereby on the number of boxes which can be effectively used per unit of brickwork in this area of the furnace are too severe to permit a uniform and really efficient reduction of the average temperature of the lining.

Furthermore, the necessity for scattering cooling boxes throughout the mass of brickwork in order to balance the weakening produced by their use, expresses itself in localized cooling, simultaneously demonstrating the value of cooling as such and the deleterious effects caused by its localization. From observations of blast fur-

naces, the wear on the lining is not uniform but is greatly reduced in the areas where heat absorption by the cooling boxes is rapid enough to keep the temperature below a predetermined level and deeply penetrates the brickwork in the areas between the cooling members, at which point the heat removal is greatly reduced by the insulating effect of the surrounding masonry. Projections and indentations in the lining so formed pronouncedly interfere with a uniform descent of the charge, and reduce the lining life to that of its weakest part. This effect appears to be the most pronounced around the mantle plate, and the lower portion of the inwall, where the effect of high temperature, high heat, and abrasion is the greatest and presents the least dependable part of blast furnaces, which is, furthermore, the most difficult to repair under operating conditions.

Heavy lining required at the mantle plate by contemporary furnace designs leads also to undesirable conditions in respect to carbon disintegration. Unless refractories used are entirely free from iron inclusions or these inclusions are present in a chemical form preventing their easy reduction, there is always a possibility of carbon disintegration of the brick involved. This phenomenon has received much study in the hands of both practical men and scientists and was finally reduced to a mechanism associated with the reduction of iron oxide to metallic iron by carbon monoxide. Metallic iron, resulting from decomposition, in its turn acts as a catalyst leading to the decomposition of carbon monoxide to free carbon which precipitates between the individual grains of the brick creating a sufficient pressure to completely overcome, or at least greatly decrease, the cohesion among them. As these reactions take place at a temperature much lower than observed at the inside surface of the lining, a critical zone is created within the body of it where the radiation to the outside balances the heat input from the inside, creating a temperature range leading to this decomposition. This zone is usually established at a certain distance below the inside surface of the lining and gradually advances towards the shell with the wear of the inside layers of the brick. On this account, the wear of the lining up to the point of reaching the original decomposition zone is comparatively slow, but, as soon as this brick is consumed, lining falls very rapidly and out of all proportions to its normal wear.

Necessity of operating the lower inwall under conditions approaching marginal safety requirements expressed itself in the impossibility of using blast furnaces of common design for production of iron alloys requiring for their manufacture a somewhat higher temperature range, such as spiegel or ferrosilicon with higher contents of the latter element. The effect of practice associated with their melting on the refractory lining of the furnace is quite pronounced. While properly water cooled boshes and hearth are able to withstand it for a considerable length of time, the lower inwall lining is so rapidly and severely affected that switching the burden to the making of these alloys is permissible only in the latest stages of a furnace campaign when the lining is gone far enough to disregard it as an operating factor.

These aspects of furnace design are well known to blast furnace technicians, and many attempts have been made already to remedy the situation in some appropriate manner, among which a par-

ticularly important place is occupied by the so-called "thin lining." This lining consisted of only a few layers of bricks applied to a shell, and protected by an artificial cooling of the shell to produce a temperature gradient adequate to cause heat elimination at a rate sufficient for preventing an excessive attack on refractories. Furnaces incorporating the above idea have been built and run for a considerable time but with 10 rather indefinite success. The chief difficulties associated with this type of lining were principally connected with inadequacy of shell cooling. As a general rule, either sprinkling or allowing water to run over the surface of the shell were 15 the only means available for heat removal. Thin-lined furnaces and other installations incorporating the principle of shell cooling from the outside failed, however, in achieving the desired results and led to the return of the presently accepted thick lining.

Furthermore, any radical changes in the design of this portion of the furnace cannot be introduced without pronounced objection, because the lines of the furnaces, after the evolution covering centuries, are standardized to the extent that any modification in them beyond changing an angle of inclination by a very few degrees, cannot be tolerated from the standpoint of efficiency and the large investment involved. On 30 this account, any modifications which might be introduced have to be adopted in connection with existing lines of the lining, leaving the design of the shell alone open to further adjustments.

According to the present invention, the difficulties and inconveniences associated with the present construction of the lower portion of the inwall are eliminated in a simple and effective manner by raising the mantle plate and replacing a portion of the shell lined with the refractories, i. e., the portion extending from the mantle to the jacket of the boshes, with a cooling and reinforcing jacket of a special construction.

Accordingly, it is the general object of the present invention to provide an improved blast furnace constructed in such a manner that the aforementioned difficulties are eliminated, and at the same time, a construction which is strong and rugged and possesses the required characteristics of a good furnace.

It is another object of the invention to provide an improved blast furnace which is simple and inexpensive in its construction, and, at the same time, efficient and effective in its use.

It is a further object of this invention to provide an improved lower inwall for blast furnaces and the like which may be easily and conveniently incorporated with existing blast furnaces at a minimum amount of expense.

It is still another object of this invention to provide an improved cooling and reinforcing jacket for the lining of the lower inwall of blast furnaces and the like.

Various other objects and advantages of this invention will be more apparent in the course of the following specification and will be particularly pointed out in the appended claims.

In the accompanying drawings there is shown, for the purpose of illustration, an embodiment and several modifications thereof which my invention may assume in practice.

In these drawings:

Figure 1 is a vertical sectional view through the side of a blast furnace of the conventional type;

Figure 2 is a similar view through the side of a blast furnace constructed in accordance with the

present invention showing my improved cooling and reinforcing jacket incorporated therewith;

Figure 3 is a front elevational view of a section of the improved cooling and reinforcing jacket of my invention showing the preferred form of construction;

Figure 4 is a sectional view taken on line IV—IV of Figure 3;

Figure 5 is a sectional view taken on line V—V of Figure 3;

Figure 6 is a cross-sectional view of a modified form of construction of the jacket as shown in Figure 3;

Figure 7 is a cross-sectional view of another modified form of construction thereof;

Figure 8 is a sectional view taken on line VIII—VIII of Figure 7;

Figure 9 is a cross-sectional view of another modified jacket construction;

Figure 10 is a cross-sectional view of a further modified jacket; and

Figure 11 is a cross-sectional view of still another modified jacket construction.

Referring more particularly to the drawings there is shown for the purpose of illustration, a vertical section through the wall of a conventional type blast furnace as presently used. In such a construction, there is provided a hearth section 2 having a bosh section 3 arranged directly thereabove with bosh plates 4 arranged in the wall of the furnace for cooling the same. Directly above the bosh section 3, there is arranged a mantle plate 5 which encircles the furnace and which is supported by columns 6 positioned on the outer side of the furnace in a well known manner. Directly above the bosh section 3 and the mantle plate 5, there is positioned a relatively thick lower inwall section 7 having a series of cooling boxes 8 arranged in the refractory brickwork thereof for cooling the same. There is provided a cooling plate 9 which encircles the hearth section for cooling the same. In such a conventional construction, the mantle plate is usually located at a point of about 25 to 30 feet above the bottom of the hearth. This corresponds to a temperature range within the lower inwall section from about 2250 to 2450° F. which results in an excessive softening of the brick supporting the superimposed lining.

According to the present invention, as shown in Figure 2 of the drawings, which is a vertical section through the wall of my improved blast furnace, a section similar to that shown in Figure 1, the hearth section 2^a and the bosh section 3^a are substantially the same as in the conventional type. However, in my construction, the mantle plate 5^a is positioned at a point above the lower inwall section 7^a and is supported as before, by columns 6^a. The refractory lining of the lower inwall section 7^a is relatively thin and there is arranged therearound and directly next thereto and extending substantially between the mantle plate 5^a and the bosh section 3^a, an annular cooling and reinforcing jacket 10. This jacket is preferably supported by suitable means (not shown) carried by the mantle plate 5^a or in any other suitable manner. There is arranged around the hearth section 3^a, a cooling and reinforcing jacket 12 similar to the jacket 10 which will be described hereafter in detail. In the proposed construction the mantle plate is raised and positioned at a point of about 35 to 40 feet above the bottom of the hearth, or, in other words, to the level at which the refractory lining is subjected to a temperature varying from about

1800 to 2100° F. and consequently disposed in the range resulting in strength and resistance amply capable to withstand the attack of operating conditions for a considerable length of time. By providing such a construction, it will be seen that the necessity of providing a relatively thick wall at the mantle plate as normally and above as a means for obtaining the necessary safety factor from the abrasion resistance standpoint, is eliminated, and makes the use of cooling boxes superfluous, which, in its turn, permits a further thinning of the lining.

It will be seen that the position of the mantle plate in the proposed construction does not involve any changes whatsoever in the inside lining of the furnace, for the reason that the contour of the lining is not affected by the changes in outside dimensions of the shell or in reducing the thickness of the lining itself.

As hereinbefore stated, the cooling and reinforcing jacket 10 extends substantially from the mantle plate 5^a to the bosh section 3^a, and is intended to replace the corresponding portion of the shell with its thick lining of refractories, as shown in the conventional furnace design. This jacket is constructed in such a manner as to have sufficient strength and to provide a refractory lining surrounded by it with suitable resistance to temperature and chemical action to which this portion of the furnace is subjected. The jacket is preferably constructed from steel or other metals selected to have sufficient strength and formed to coincide with the external outlines of this portion of the furnace shell.

In order to increase the protecting power of the relatively thin refractory lining of the lower inwall section 7^a, the jacket 10 should be constructed in such a manner so as to assure a uniform abstraction of heat over the entire area of the exposed surface so as to completely eliminate the deleterious effect of localized cooling as experienced by the use of cooling boxes. Accordingly, it is desirable that the jacket 10 be constructed so as to provide therewithin a labyrinthic or sinuous passageway for conveying the cooling water or fluid over the entire area of the jacket. Such a construction may be provided in a multitude of ways, for example, by sealing, at a certain distance from the inner jacket plate, a sheet of steel

or any other suitable material having a thickness sufficient only to withstand the pressure of water applied for cooling purposes and providing, in the space between the jacket plate and this sheet, a series of baffles to control the circulation of the water or fluid in any desired manner.

By adjusting the rate of water flow through the jacket, it will be seen that the cooling effect exerted on the refractories can be regulated to meet the requirements of melting practice. It will be understood that when common grades of cast iron are made in a blast furnace, a comparatively low rate of heat removal is sufficient to compensate for the heat produced by the charge. By increasing properly the heat elimination to take care of hotter charges associated with ferro-alloys melting, it will be seen that the lower inwall lining of the furnace is protected from premature failure. Accordingly, it will be seen that a furnace constructed in accordance with the present invention extends the use of a blast furnace to the manufacture of alloys heretofore requiring for their manufacture more expensive equipment and methods.

Operating conditions associated with the making of certain ferro-alloys occasionally require a

cooling rate to be applied to furnace refractories which is difficult to achieve by means of equipment made of steel. While steel is amply satisfactory from the standpoint of strength, it is well known that this metal has a somewhat low coefficient of heat conductivity. When a desired rate of heat abstraction from the exposed surface of the refractory lining exceeds the heat absorbing capacity of a cooling jacket, when made of steel, as proposed, the rate of heat abstraction may be increased by substituting for the steel a metal having a greater coefficient of heat conductivity, such as copper and some of its alloys.

It will be understood that by providing a thin lining in the lower inwall section of the blast furnace, in accordance with the teachings of the present invention, there results a further advantage of preventing to a great extent carbon disintegration of the brick. It is well known that a very considerable difference between heat conductivities of metal and refractories contracts the zone of temperature at which this phenomenon takes place to a fraction of that observed in the body of a heavy lining and concentrates it at the outer faces of the brick, i. e., the face coming in contact with the cooling plates. Furthermore, the disintegration zone, once established by the thermal balance, is maintained in the same position instead of being allowed to travel outwardly, as in the case of the conventional thick linings.

Although many types of cooling and reinforcing jackets are suitable for achieving the objects of my invention, I prefer to use a jacket constructed in a manner as shown in the several embodiments of Figures 3 through 11 of the drawings. The jacket in each of these embodiments includes a relatively thick arcuated inner plate 13 which is adapted to be disposed directly next to the outer side of the refractory lining of the inner wall section 7^a of the furnace, as shown in Figure 2. It will be understood that the plate 13 reinforces the thin lining of the lower inwall section 7^a. The jacket is preferably made in sections with the abutting edges of the plates 13 welded together as at 13^a so as to provide an annular arrangement which completely encircles the lower inwall section of the furnace. In the preferred construction, as shown in Figures 3 through 5 of the drawings, there is arranged on the outer side of the arcuated plate 13, a plurality of vertically extending spaced apart rectangular-shaped members 14 having one of their longitudinal edges welded to the plate 13 so as to provide channels therebetween. The successive members 14 terminate a short distance from the top and bottom of plate 13 so as to provide a continuous sinuous passageway around and between the members 14. There is securely welded to the outer longitudinal edges of the members 14 a relatively thin arcuated plate 15 which corresponds in size to the plate 13 and is spaced therefrom by the members 14. There are welded to the ends of members 14 and the plates 13 and 15, top and bottom plates 16 and 17, respectively, so as to provide an enclosed structure. It will be understood, as hereinbefore stated, that the jacket is preferably made in sections primarily for the purpose of handling and ease in assembling, and when assembled in place around the outer shell of the inner wall, the edges are secured together preferably by means of welding or in any other suitable manner. There is provided means, such as cooling pipes 19 and 20, for conveying the cooling fluid into and out of passageways in each section.

The construction, as shown in Figure 6 of the drawings, is similar to the preferred construction but differs therefrom in that the plate 15 is not one continuous plate. In this construction, the 5 passageway formed between each of the vertically extending members 14 is enclosed by a rectangular-shaped plate 21, and the edges of each of the plates are successively welded to each and to alternating members 14 as at 22.

10 In Figure 7 of the drawings, there is shown another modification of the cooling and reinforcing jacket 10 of my invention. In this construction, there is provided the relatively thick heavy plate 13, as before, and on the outer surface thereof 15 there is disposed a plurality of vertically extending structural members 23 having substantially a U-shaped cross section. The ends of the leg portions of each of the U-shaped members are welded as at 23^a to the outer surface of the plate 13 and to the leg of the next succeeding and abutting U-shaped member so as to provide a series of U-shaped parallel channels 24 between the U-shaped members 23 and the plate 13. A portion of the material of the leg portions of each 20 of the members 23, at the top and bottom of alternate plates, are cut away as at 25, as shown in Figure 8, and there is arranged between the leg portions and disposed around the cut away portions formed therein, preferably, a channel-like member 26 for interconnecting the channels 24 between successive U-shaped members so as to provide a continuous sinuous passageway on the outer surface of the plate for conveying the cooling fluid therearound. Between the sections of 30 the jacket there is provided, preferably, a plate member 27 which is welded to the outer surfaces of U-shaped members 23 positioned at adjacent ends of the sections so as to provide a channel 35 28 between each of the sections.

40 In Figure 9 of the drawings, there is shown a slight modification of the construction as shown in Figure 7. In this construction, there is provided a plurality of vertically extending members 29 which are arcuated or substantially open U-shaped in cross section. They are disposed on the outer side of the plate 13 in side-by-side relationship with one of the longitudinal edges thereof welded to the outer surface of the plate with the opposed longitudinal edge welded to the outer side of the next succeeding member 29 so as to provide an irregular-shaped passageway or channel 45 between each of the members 29 and the outer side of the plate 13. A portion of the edge of each of the plate members 29 welded to the plate 13 at 50 the top and bottom of alternate plates, is cut away as at 30 so as to interconnect the channels whereby a continuous sinuous passageway is formed along the outer side of the plate 13 for conveying the cooling fluid therealong. As before, there is provided preferably a rectangular plate 31 which is welded to the outer sides of the adjacent members 29 on the ends of each of the sections for 55 providing an enclosed channel at this point.

In the embodiment of my invention, as shown 60 in Figure 10 of the drawings, there is provided a plurality of vertically extending angle members 32 which are disposed in side-by-side relationship on the outer side of the plate 13. In this modification, the end of one of the legs of each of the members 32 is securely welded to the outer surface of the plate 13 and the edge of the other leg of each of the members is welded to the outer surface of the next succeeding member 32 so as to provide an enclosed channel between two adjacent members and the outer side of the plate. 70 75

As in the construction shown in Figure 9, a portion of the leg which is welded to the plate 13 is removed, from the top and bottom of alternate plates, so as to interconnect the channels formed by the members 32 whereby a continuous sinuous passageway is provided along the outer side of the plate 13.

In Figure 11 of the drawings, there is shown still another modified form of construction of the jacket. In this construction, there is provided a plurality of vertically extending T-shaped structural members 33 which are disposed in side-by-side relationship on the outer side of the plate 13. The bottom edge of the upright or vertical portion of each of the T-shaped members 33 is welded to the outer surface of the plate 13, and the adjacent edges of the cross portions of the T-shaped members are welded to the abutting edges of the cross portions of adjacent T-shaped members positioned to either side thereof so as to provide an enclosed channel between two succeeding T-shaped members and the outer side of the plate 13. Likewise, in this construction, a portion of the upright portion of the T-shaped members 33, at the top and bottom of alternate members, is cut away or removed so as to interconnect the channels, thus again providing a continuous passageway on the outer side of the plate. It will be understood that in all these modified constructions, there is provided top and bottom plates, similar to plates 16 and 17 in the preferred construction for enclosing the respective structures. Also, it will be understood that in each of these constructions, there is connected to the channel or passageways formed, suitable means, such as inlet and outlet pipes, for introducing the fluid thereinto and for conveying the same therefrom similar to the pipes 19 and 20 in the preferred construction.

While the structural members 14, 23, 29, 32 and 33 of the various modifications, are shown arranged vertically on the plate 13, it will be understood that they may be arranged horizontally or diagonally, if desired, but it is believed that the vertical arrangement is the most satisfactory, and practical, because of the ease in fabrication and assembling thereof.

While the cooling and reinforcing jacket heretofore described is particularly adapted for creating conditions of an adequate heat absorption in the lower inwall portion of the furnace, it will be understood that such a jacket can be used to advantage in any part of the furnace where an efficient and uniform cooling is required, as for example, around the hearth. In fact it is desirable that the cooling and reinforcing jacket of the construction above described be used as the cooling jacket 12 for the hearth, as shown in Figure 2 of the drawings.

While I have shown and described several specific embodiments of my invention, it will be understood that these embodiments are merely for the purpose of illustration and description and that various other forms may be devised within the scope of my invention, as defined in the appended claims.

I claim:

1. A jacket for cooling and reinforcing the lower inwall section of blast furnaces and the like comprising a plurality of arcuate-shaped sections continuously arranged around the furnace wall having their edges welded to each other so as to provide an annular arrangement, each of said sections consisting of an arcuate-shaped relatively thick metallic inner plate which is

adapted to be disposed directly next to the furnace wall, a plurality of members arranged on the outer surface of said plate so as to provide a continuous sinuous passageway along the outer surface of said plate, and means for introducing a cooling fluid into said passageway for cooling said plate.

2. A jacket for cooling and reinforcing the lower inwall section of blast furnaces and the like comprising a plurality of sections continuously arranged around the furnace wall having their edges welded to each other so as to provide an annular arrangement, each of said sections consisting of an arcuate-shaped relatively thick inner plate which is adapted to be disposed directly next to the furnace wall, a plurality of substantially parallel members disposed vertically on the outer surface of said plate and securely welded thereto with said members being constructed and arranged so as to provide a continuous sinuous passageway along the outer surface of said plate, and means for introducing a cooling fluid into said passageway for cooling said plate.

3. A jacket for cooling and reinforcing the lower inwall section of blast furnaces and the like comprising a plurality of sections continuously arranged around the furnace wall having their edges welded to each other so as to provide an annular arrangement, each of said sections consisting of an arcuate-shaped relatively thick inner plate which is adapted to be disposed directly next to the furnace wall, a plurality of spaced apart parallel rectangular-shaped metallic members disposed vertically on the outer surface of said plate having their edges welded to the outer surface thereof so as to provide a channel successively between each of them with successive members terminating short of the extreme bottom and top of said plate so as to provide a continuous sinuous passageway along the outer surface of said plate, an arcuate-shaped outer plate substantially conforming in size to said first mentioned plate welded to the outer edges of said rectangular members so as to be spaced from said first mentioned plate and to enclose the channels between said parallel members, top and bottom plates welded to both of said inner and outer plates so as to provide an enclosed structure, and means for introducing a cooling fluid into said continuous passageway for cooling said first mentioned plate.

4. A jacket for cooling and reinforcing the lower inwall section of blast furnaces and the like comprising a plurality of arcuate-shaped sections continuously arranged around the furnace wall having their edges welded to each other so as to provide an annular arrangement, each of said sections consisting of an arcuate-shaped relatively thick metallic inner plate which is adapted to be disposed directly next to the furnace wall, a plurality of parallel U-shaped channel-like members disposed vertically on the outer surface of said plate with the ends of the leg portions of each of said U-shaped members abutting each other and securely welded to said plate and to each other successively therearound so as to provide an enclosed channel between each of said U-shaped members and said plate, and means interconnecting alternately the top and bottom of the enclosed channels formed by said U-shaped members and said plate so as to provide a continuous sinuous passageway along the outer surface of said plate, top and bottom plates welded to the ends of said U-shaped members and said first mentioned plate so as to provide an enclosed

structure, and means for introducing a cooling fluid into said passageway for cooling said first mentioned plate.

5. A jacket for cooling and reinforcing the lower inwall section of blast furnaces and the like comprising a plurality of arcuate-shaped sections continuously arranged around the furnace wall having their edges welded to each other so as to provide an annular arrangement, each of said sections consisting of an arcuate-shaped relatively thick metallic inner plate which is adapted to be disposed directly next to the furnace wall, a plurality of parallel channel-like members having an arcuate-shaped cross section disposed vertically on the outer surface of said plate, one of the longitudinal edges of each of said members securely welded to the outer surface of said plate with the opposed longitudinal edge of each of them securely welded to the outer side of the next successive member around the plate so as to provide an enclosed channel between each of said members and said plate, each of said channel-like members having a portion removed therefrom alternately at the top and bottom of successive members at a point adjacent the edge welded to the plate so as to interconnect the channels formed thereby whereby a continuous sinuous passageway is provided along the outer surface of said plate, top and bottom plates welded to the ends of said channel-like members and said plate so as to provide an enclosed structure, and means for introducing a cooling fluid into said passageway for cooling said plate.

6. A furnace of the class described including a

hearth having a bosh section arranged thereabove, a relatively thin lower inwall section made of a refractory material arranged above said bosh section, a mantle arranged around said furnace at a point immediately above said lower inwall section, and a cooling and reinforcing jacket consisting of a relatively thick metallic plate arranged peripherally around and directly next to the thin refractory lower inwall section of said furnace so as to completely encircle the same and extending substantially between said mantle and said bosh section, and means arranged on the outer side of said plate forming sinuous passageways for continuously conveying a cooling fluid around the outer surface thereof for cooling the same.

7. A furnace of the class described including a hearth having a bosh section arranged thereabove, a relatively thin lower inwall section made of a refractory material arranged above said bosh section, a mantle arranged around said furnace at a point immediately above said lower inwall section, and a cooling and reinforcing jacket consisting of relatively thick metallic plates integral 20 ly joined together arranged peripherally around and directly next to the thin refractory lower inwall section of said furnace so as to completely encircle the same and extending substantially between said mantle and said bosh section, and 25 means arranged on the outer side of said plates forming sinuous passageways for continuously conveying a cooling fluid around the outer surface thereof for cooling the same.

GEORGE A. WHITEHURST.
